UNITED STATES PATENT OFFICE

153,395

DESIGN FOR AN ASH TRAY

John H. Roethel, Detroit, Mich., assignor to
Roethel Engineering Corporation, Detroit,
Mich., a corporation of Michigan

Application January 21, 1948, Serial No. 143,918

Term of patent 7 years

(Cl. D85—2)

To all whom it may concern:

Be it known that I, John H. Roethel, a citizen of the United States, residing at Detroit, county of Wayne, State of Michigan, have invented a new, original, and ornamental Design for an Ash Tray, of which the following is a specification, reference being had therein to the accompanying drawings, forming a part thereof, in which

Fig. 1 is a top plan view of an ash tray, showing my new design.

Fig. 2 is a side elevation of the ash tray shown in Fig. 1.

Fig. 3 is a section taken substantially through lines 3—3 of Fig. 1 looking in the direction of the arrows.

I claim:

The ornamental design for an ash tray, substantially as shown.

JOHN H. ROETHEL.
